United States Patent

Des. 238,198

Patented Dec. 23, 1975

238,198

PENDANT

Marcia Bell Fear, Youngstown, Ohio, assignor to Marcia Bell Fear, Youngstown, Ohio

Filed June 10, 1974, Ser. No. 478,154

Term of patent 14 years

Int. Cl. D11—01

U.S. Cl. D45—16 B

FIG. 1

FIG. 2

FIG. 3

FIG. 1 is a perspective view of a pendant showing my new design;

FIG. 2 is a front elevational view, the back being identical thereto; and

FIG. 3 is an edge elevational view.

I claim:

The ornamental design for a pendant, as shown and described.
